BICYCLE ATTACHED TOY MACHINE GUN

Evan S. Connell, Jr., Santa Cruz, Calif.

Application September 18, 1951, Serial No. 247,116

6 Claims. (Cl. 46—175)

1

The present invention relates to a toy machine gun attachment for a bicycle, or the like. It consists of the combinations, constructions, and arrangement of parts, as hereinafter described and claimed.

Among the various objects of this invention, I propose to provide a toy machine gun, which is adapted to be mounted on a bicycle, or the like, at substantially handle-bar level thereon, thus allowing the gun to be actuated and directed conveniently by the cyclist. Simulated firing is obtained by moving a spring-like finger into engagement with the spokes of a bicycle wheel during rotation of the latter, producing noises resembling the firing of a machine gun. The device is intended for amusement purposes, the rate and volume of simulated firing being controlled by the cyclist. The device will be particularly appealing to youngsters.

Another and important object of the invention is to produce an attachment of the character described, which may be readily secured to a bicycle, or the like, without requiring any alterations in the latter.

Moreover, I propose to provide a toy machine gun attachment that is simple in construction, durable and efficient for the purpose intended, and easily adjusted to different sizes of bicycles.

Other objects and advantages will appear as the specification continues. The novel features will be pointed out in the claims hereunto appended.

Drawing

For a better understanding of the invention, reference should be had to the accompanying drawing, forming part of this application, in which:

Figure 1 is an elevational view of the forward portion of a conventional bicycle, disclosing my toy machine gun mounted thereon;

Figure 2 is a horizontal sectional view taken along the plane II—II of Figure 1, illustrating the spoke-engaging finger and the mounting band thereof; and

Figure 3 is a vertical sectional view of the universal connection disposed between the gun and the steering bracket of the bicycle, this view being taken along the line III—III of Figure 1.

While I have shown only the preferred form of my invention, it should be understood that various changes, or modifications, may be made within the scope of the annexed claims without departing from the spirit thereof.

2

Detailed description

Referring to the drawing, it will be recognized from Figure 1 that I have illustrated the forward portion of a conventional bicycle, which is designated generally at A. It includes the usual frame 10 having a fork 11 rotatably supported therein, this fork having a front wheel 12 mounted therebetween on an axle 14. Of course, the two legs 11a of the fork straddle the wheel in the customary manner.

As shown in Figure 1, a steering bracket B is secured to the upper end of the front fork by a bolt 15. This same bracket is fashioned with a clamp 16 into which handle-bars 17 are inserted. It is well known that the handle-bars are employed for steering the bicycle, and that spokes 18 of the wheel must pass in consecutive order between the legs 11a as the wheel 12 is turned.

For the purpose of mounting a toy machine gun C on the bicycle at substantially handle-bar level, and at the same time permit the gun to be pointed by the cyclist in desired directions, I make use of a universal connection indicated at D in Figures 1 and 3.

In its structural features, the connection D has been shown as including an L-shaped member 19 having its horizontal leg 19a secured to the steering bracket B by the bolt 15 previously mentioned. This leg is fashioned with a saddle 19b on its underneath side so as to embrace the forwardly extending part 20 of the steering bracket in the manner clearly disclosed in Figure 3.

It will be observed that the member 19 has a ball 21 fixed to the top of its upright leg 19c. The toy machine gun is provided with a depending tube 22, which is directed toward the ball 21. I have shown a cap 23 for retaining the ball and the tube together, while allowing universal movement therebetween. In order to frictionally retain the gun in adjusted position, I have provided a spring-pressed shoe 24 on the interior of the tube 22, which bears against the ball 21 in the manner of a brake.

It is desirable to mount the gun C for universal movement so that the cyclist can point it in the proper direction, thus contributing to the appeal of the device to youngsters. However, various types of universal connections may be resorted to for this purpose, and I do not wish to be limited to the specific details of the connection D described above.

The toy gun C is fashioned with a pistol grip

25, which is designed for grasping by the cyclist. Inasmuch as this grip is disposed on about the level as the grips 17a of the handle-bars, it will be very convenient for the cyclist to utilize one hand for directing the muzzle 26 in the desired direction at a simulated target. The particular design of the gun may be changed to suit the fancy of the manufacturer.

For simulating machine gun fire, and thereby contributing to the appeal of the device to youngsters, I have provided a resilient strip-like spoke-engaging finger E, which is actuated by a cable F and a trigger 27, the latter being pivotally secured at 28 to the body of the gun. This finger may be fashioned from a leaf-spring, with the "set" thereof designed to normally position the free tip 29 of the spring out of engagement with the path 30 defined by the rotating wheel spokes 18 (see Figure 2).

As illustrated in the drawings, a band 31 is adjustably clamped to one of the legs 11a of the steering fork 11 by a bolt 32. In Figure 2, I show the finger E as having its end 33 anchored to this band. Quite obviously, the band 31 may be adjusted vertically along the length of the fork leg so that the cable F will be taut when the finger occupies its normal full-line position in Figure 2, that is, the finger tip 29 is out of contact with the rotating wheel spokes.

The finger E is fashioned with a loop 34 in the intermediate portion thereof, and the cable F extends across this loop. This cable is guided through an eyelet 35, and has its lower end fastened by a ring 36 provided on the flexible portion 37 of the spring finger. As illustrated in Figure 2, the finger portion 37 extends at an angle relative to the plane of the wheel, and will yield as each spoke strikes the tip 29 so as to permit passage of the spoke.

It will be apparent that when the reach 38 of the cable F is pulled upwardly by retracting the trigger 27, the portion 37 of the spring finger will be flexed into the dot-dash line position shown in Figure 2, thus constricting the loop 34. At this time the end 29 of the finger will strike successive spokes of the wheel during rotation of the latter, producing a noise simulating the firing of the gun. As soon as pressure is relaxed on the trigger, a suitable spring 39 will return the trigger to its normal position, as shown in Figure 1, and the finger tip 29 will move out of engagement with the spokes. Thus the noise simulating the machine gun firing will cease.

In order to guide the cable F within the gun, I have provided pulleys 40 and 41 over which it is trained. This will preclude the cable from wearing and will lead it to the trigger from the proper side of the latter so that retraction of the trigger will operate to pull the reach 38 upwardly. This reach is disposed adjacent to the universal connection D in order that mere swinging of the gun will not operate to flex the finger E into engagement with the spokes of the wheel.

Summary of operation

Assuming that the toy machine gun C is supported by the universal connection D on the steering bracket B, as illustrated in Figure 1, the band 31 should be adjusted along the length of the fork leg 11a until the cable F is taut and the free end 29 of the resilient finger E is out of contact with the wheel spokes 18. At this time, the bolt 32 should be tightened so as to hold the band 31 in place.

When the cyclist desires to "fire" the gun, the

grip 25 and the trigger 27 may be grasped readily in one hand, leaving the other hand of the cyclist free to steer the bicycle by means of the handle-bars 17. The gun may be pointed in the desired direction. Upon retracting the trigger, the cable reach 38 will be drawn upwardly, resulting in moving the finger tip 29 into the path 30 of the rotating spokes 18. As each spoke strikes the resilient finger E, a noise will be produced that will simulate the "firing" of the gun.

As soon as pressure is relaxed on the trigger, the resilient finger E will return to its full line position shown in Figure 1, moving the tip 29 thereof out of engagement with the spokes of the rotating wheel and stopping the "firing" of the top machine gun.

I claim:

1. In an attachment of the character described: a toy machine gun, including a trigger; means mounting this gun on a bicycle, or the like, at substantially handle-bar level thereon in a position for grasping and direct aiming of the gun by a cyclist, while riding the bicycle; a resilient finger having means connected thereto for supporting the finger on a part of the bicycle adjacent to a wheel thereof; the finger having a free tip normally disposed out of engagement with spokes of the wheel; this finger being adapted to be flexed into a position in which the spokes will strike the tip during rotation of the wheel to produce a noise simulating "firing" of the gun; and means operated by the trigger under direct control of the cyclist for flexing the finger into the path of the wheel spokes, when desired by the cyclist, to thereby selectively "fire" the gun at will.

2. The combination as defined in claim 1, in which the mounting means for the gun includes a universal connection arranged so that the gun may be elevated, depressed and traversed in desired directions by the cyclist.

3. In an attachment of the character described: a toy machine gun, including a trigger; means mounting this gun on a steering bracket of a bicycle, or the like, in a position for grasping and direct aiming of the gun by a cyclist, while riding the bicycle; a resilient finger having means connected thereto for supporting the finger on a part of the bicycle; the finger having a free tip normally disposed out of engagement with spokes of a wheel of the bicycle; this finger being adapted to be flexed into a position in which the spokes will strike the tip during rotation of the wheel to produce a noise simulating "firing" of the gun; and means operated by the trigger under direct control of the cyclist and connected to the finger for flexing the latter into the path of the wheel spokes, when desired by the cyclist, to thereby selectively "fire" the gun at will.

4. In an attachment of the character described: a toy machine gun, including a trigger; means mounting this gun on a steering bracket of a bicycle, or the like, in a position for grasping and direct aiming of the gun by a cyclist; a band adapted to be clamped on a fork of the bicycle; a resilient finger carried by the band; the finger having a free tip normally disposed out of engagement with spokes of a wheel journalled in the fork; this finger being adapted to be flexed into a position in which the spokes will strike the tip during rotation of the wheel to produce a noise simulating "firing" of the gun; and a cable having its opposite ends connected to the trigger and finger, respectively, and being movable by the trigger under direct control of the cyclist for

flexing the finger into the path of the wheel spokes, when desired by the cyclist, to thereby selectively "fire" the gun at will; the band being adjustable along the length of the fork to tighten the cable taut.

5. The combination as defined in claim 4, in which mounting means for the gun includes a universal connection arranged so that the gun may be elevated, depressed and traversed in desired directions by the cyclist; the cable having 10 a reach disposed adjacent to this universal connection so that swinging of the gun will not operate to flex the finger into engagement with the spokes of the wheel.

6. In a toy machine gun attachment for a bicycle, or the like: a resilient strip-like finger defining a loop in an intermediate portion thereof; the finger further defining end sections disposed on opposite sides of the loop and diverging relative to one another; means for securing one 20 end section of the finger to a leg of a bicycle fork, with the other end section being free and directed toward spokes of a wheel journalled in the fork at an angle relative to the general plane of the wheel; the loop having a "set" therein so that the free end section of the finger normally will be out of engagement with the spokes

during rotation of the wheel; a cable extending across the loop; means anchoring one end of this cable to one end section of the finger; and an eyelet mounted in the other end section of the finger; the cable being guided through this eyelet for constricting the loop and for moving the free end section of the finger into the path of the wheel spokes upon pulling the other end of the cable.
